HOWARD S. FOLKER, OF OROVILLE, CALIFORNIA, ASSIGNOR TO THE NATIONAL SAFETY APPLIANCE COMPANY, OF SAN FRANCISCO, CALIFORNIA, A CORPORATION OF CALIFORNIA.

AUTOMATIC TRAIN-STOP.

1,284,284.

Specification of Letters Patent. Patented Nov. 12, 1918.

Application filed September 3, 1916. Serial No. 118,980.

To all whom it may concern:

Be it known that I, HOWARD S. FOLKER, a citizen of the United States, and a resident of Oroville, county of Butte, and State of California, have invented certain new and useful Improvements in Automatic Train-Stop, of which the following is a specification.

This application is in part a continuation 10 of my prior application Serial No. 43,592, filed August 4th, 1915, for "diaphragm valves," Serial No. 55,424, filed October 12th, 1915, for "controlling means for automatic train stops," and Serial No. 74,325, filed 15 January 26th, 1916, for "controlling means for automatic train stops."

My invention hereinafter described and claimed relates to improved constructions and arrangements of valves which are automatically operated by differences in fluid pressure and controlled in their operation by an electro-magnet, the invention being designed particularly to be used for automatically applying air-brakes to the wheels of a 25 railway train.

The construction and arrangement is such that the venting of a portion of the fluid pressure in certain chambers of the valve mechanism will cause the air brake applying mechanism or train stop to operate, thereby giving a service application of the automatic air brakes at any predetermined reduction of brake pipe pressure in a manner similar to that which would be given by 35 the operation of the engineer's brake valve.

The objects of my present invention will now be specifically set forth, but in addition thereto, it is to be noted that it has been my purpose to attain some of the objects of 40 the invention described and claimed in my prior applications which are specifically mentioned above, by the utilization of new and improved constructions and arrangements of parts.

One of the particular objects of this invention, is to combine in one structure, a plurality of automatically operating valve mechanisms controlled by an electro-pneumatic valve.

Another object is to provide a valve controlling mechanism consisting of a pair of double diaphragms, the effective area of two diaphragms (one of each pair) being the greater than the effective area of the other 55 two (one of each pair); the deflection of

these diaphragms controlling the movement of a puppet valve into and out of its seat for a purpose to be hereinafter described.

Another object is to so construct a valve mechanism to be operated by the aforesaid 60 diaphragms so that when fluid pressure is vented in a particular chamber, it will cause a valve to open, thereby reducing the fluid pressure in the brake pipe to a pre-determined amount, thereby giving a service application of the brakes, and then cause the aforesaid valve to close in its seat.

Another object is to so construct and position a valve in relation to the other elements of a train stopping mechanism so as to 70 make it impossible to open the valve for supplying pressure to the brake pipe until after the train has come to a stop. When this function is effected, the engineer is required to dismount from his cab in order to 75 operate the release mechanism, yet the construction and arrangement is such that the valve may be opened after the brakes have been initially applied in order to take air from the brake pipe for the purpose of 80 effecting a heavier and quicker application of the brakes.

Another object is to provide a construction by means of which the initial brake pipe pressure is stored for use as a base for 85 the brake pipe applications, and for this purpose, I provide a suitably located reservoir, which will be hereinafter called the "initial pressure reservoir."

Another object is to provide a normally 90 open controlling means in the train stop mechanism to control the flow of brake pipe pressure to the reservoir. This controlling means consists of a valve mechanism so related to the other elements that the venting 95 of a portion of the fluid pressure into one of the chambers will cause the normally open valve to close, thereby cutting off communication between the brake pipe and the initial pressure reservoir.

Another object is to provide a construction which is simple, yet certain and sensitive in its operation and which will give a warning signal should a leak occur.

Other objects will appear from the subjoined description and claims.

Referring to the drawings forming a part of this specification:

Figure 1 is a combined structural and dia- 110 grammatic view of my installation, certain

portions of the structure being shown in section and other portions in elevation, and the several valves in their normal positions.

Fig. 2 is a longitudinal section with parts 5 in elevation of my combined automatic valve structure used in the installation, the valves being shown in elevation and in their normal positions.

Fig. 3 is a longitudinal section, with parts 10 in elevation of my improved electro-pneumatic valve.

Fig. 4 is a structural detail.

Fig. 5 is a horizontal section through the line 5—5 of Fig. 2.

15 In the drawings in which the same reference characters refer to like parts in the several views;

A is the usual engineer's automatic brake valve which is conventionally shown and 20 which is of the flat rotary type having many ports (not shown in the drawings), B is the electro-pneumatic controlling valve, C the automatic train stop valve mechanism as a whole, which mechanism comprises three 25 sections D, E and F which are secured together by suitable bolts not shown, and which are provided at their juncture with each other with suitable gaskets, all of which are so arranged as to make air tight joints 30 between them for the purpose of insuring against leakage between the several air passages. G is the initial pressure reservoir and H is the main pressure reservoir.

The section E of the train stop valve mechanism C is provided with communicating chambers 5 and 6 between which is located the valve seat 7 for the non-release valve 8, which valve is provided on each side thereof respectively with upwardly and 40 downwardly extending valve stems 9 and 10. A suitable fitting 11 forms a guide for the valve stem 9 and also permits the removal of the valve for repair or for the re-grinding of the valve seat 7, and this fitting 11 is 45 secured in place by a nut 12 which is provided with means for securing it to the fixed part of the section E and which is provided with a flange 12' for engaging a flange 11' on the fitting 11 to hold the fitting securely in 50 place and yet permit of its ready removal for the purpose aforesaid. A compression spring 13 surrounds the valve stem 9, its respective ends engaging with the fitting 11 and the valve 8, thereby tending at all times to close 55 the said valve upon its seat, and which assists to effect the closure of the said valve 8 upon its seat 7 when released by the mechanism hereinafter described.

60 A cylinder K is formed in the lower portion of the section E and a piston 14 operates in this cylinder and divides the same into two chambers 15 and 16. The piston 14 is provided with upper and lower cup washers 17 and 18 respectively to prevent leakage and 65 also with a centrally located annular groove

19. Any leakage of pressure past the cup washers is permitted to escape to atmosphere through the space formed by the groove 19 and the port 20 formed in the wall of the cylinder K.

The chambers 6 and 15 communicate with each other by means of the port 21 through the partition 156 which separates the aforesaid chambers. The chamber 15 communicates with a chamber 23 in the member F 70 through a passage-way past a valve 24 to be hereinafter described and a passage-way 22. The valve 24 is provided with an angular or fluted valve stem 25 which permits the passage of the pressure fluid between the chambers 15 and 23, and the said valve stem is guided in a fitting 26 secured to the partition 156 as shown, said fitting having in its under-side radially extending grooves 27 for the purpose of permitting fluid pressure to 80 pass from the chamber 15 to the chamber 23 when the valve 24 is lifted from its seat by means of the piston 14, when it assumes its uppermost position in the cylinder K. A spring 28 is situated above the valve 24 90 which tends at all times to seat the valve. The normal position of the piston 14 is shown in Fig. 2 and it is held in its uppermost position as shown by means of pressure supplied from the main reservoir H through 95 the pipes 29 and 30, the restricted passage-way 31 and the pipes 32 to the chamber 16.

The brake-pipe 33 leads to the chamber 6 in the member E through a port 34 and the pipe 35 leads from the engineer's valve A 100 through the port 36 to the chamber 5.

The section F is composed of the parts d, e, f and g and they are secured together by bolts h as shown which bolts and parts also are utilized as hereinafter described to 105 hold the double diaphragms 70 and 80 in place.

The section F is divided into three chambers 40, 41 and 42, the chamber 40 communicating with the upper part of the chamber 42 by means of a passage-way 43, which passage-way in turn communicates with the chamber 6 through another passage-way 44. The chamber 42 is divided into three sub-chambers by the pair of double diaphragms 110 70 and 80 which will be hereinafter described, thereby forming an upper sub-chamber 45, a central sub-chamber 23 and a lower sub-chamber 46. The central chamber 23 communicates by means of the passage-way 22, as hereinbefore described, with the chamber 15 and also by means of a pipe 48 to the initial pressure reservoir G and the lower chamber 46 communicates by means of a passage-way 47 to the chamber 16. The 115 chamber 41 is open at all times to the atmosphere through the restricted passage 41'. Fittings 50 and 50' are secured by suitable screw-threads respectively to the walls 51 and 52 which separate the chambers 40, 41 120 130

and 42. The fitting 50 is provided with a valve seat 53 for the valve 54 and the passage-way 55 for the fluted valve stem 56 and the fitting 50' is provided with a central 5 socket 157 within which the stem 58 is guided which stem projects from the side of the valve 54 opposite to its face. The valve stem 56 is secured to the upper arm 57' of a U-shaped piece or yoke 57 by means of a 10 swiveled joint 58' so that the valve may lodge truly upon its seat.

The lower arm 572 of the yoke 57 is suitably connected to the stud 60 which is secured to the center of one of the double diaphragms by a nut 61. To the other double diaphragm is secured a stud 62 by means of 15 a screw-thread and nut 63, the upper portion of which is provided with a guiding extension 64 which fits into a cavity 65 in 20 the lower portion of the fitting or stud 60.

The double diaphragms 70 and 80 are clamped at their peripheries respectively into their seats 71 and 81 between the annular flanges 73 and 83, and between the diaphragms are held the space rings 72 and 82. The seated members are held together by the same bolts that clamp the members *d* and *e*, *f* and *g*, together, which latter members constitute the section F. The space rings 72 and 30 82 which are held at and between the outer edges of the diaphragms are provided respectively with annular grooves 75 and 85 and are also provided with a plurality of radial vent-ports 76 and 86 as shown. The 35 said rings are so constructed with relation to the respective diaphragm seats and flanges, that the exposed surface area of the upper diaphragm 77 and the lower diaphragm 87 is greater than that of their adjoining inner diaphragms 78 and 88. The chambers formed between the single diaphragms constituting the double diaphragms are at all 40 times in communication with the normal atmosphere through the above mentioned vent-ports 76 and 86.

A plurality of space rings 79 and 89 illustrated in Fig. 5 are respectively nested between the single diaphragms forming the double diaphragms and are so constructed 50 by means of abutting radial spacing lugs 90 as to form a flexible means of support between the respective diaphragms.

As described, both pairs of diaphragms and space ring constructions are similar with 55 the exception that the diaphragm 87 has a slightly greater exposed area than the others, in order that the valve 54 may be more certainly seated, and prevented from fluttering, after an operation of the safety stop and 60 while the excess pressure, which normally exists in the main reservoir, is being built up after an application of the brakes.

The electro-pneumatic valve B is preferably secured by bolts as shown in Fig. 3 to 65 its support by a bracket 96 having a flanged

head 96'. A plurality of bolts 97 which pass through the valve head 98 are riveted at 99 to the cylindrical casing 100. Between the flanged head 96' and the valve head 98, is interposed a gasket 98' to make an air-tight 70 joint and exclude foreign matter from the valve parts. A magnet supporting flange 101 is formed integral with the rib 102 depending from the valve head 98 and supports the magnet 190, which magnet is 75 enclosed in the casing 103, said casing having a head 104 which is secured by the screw or other suitable means 105 to the flange 101. The magnet 190 is wound on a hollow core 106 through which passes a vertically movable elongated bolt 107 to the lower end of 80 which the armature 91 is secured by a flexible joint 108.

To the upper end of the bolt 107 is secured a cylindrical barrel 113 as shown, the upper 85 end of said barrel having an aperture 109 through which the valve stem 110 projects. The valve 92 is formed at the upper end of the valve stem and at its opposite end is a piston shaped head 112 which is fitted to reciprocate in the barrel 113. A helical compression spring 114 is fitted within the barrel 113, and engages with the piston 112 in order to normally force the valve 92 against its seat 93. An air passage 116 leads from 90 the valve seat to the pipe 32' which latter pipe is connected to the chamber 16 through the pipe 32 as shown in Fig. 1. The valve 92 is fitted in a chamber 117 in the valve head 98 which leads to the passage way 116. 100 Vent-holes 118 lead from this chamber to the interior of the closed casing 100 which surrounds the magnet and which is supported upon the valve head. A whistle 94 is connected to a port 120 through the side of 105 the casing. The electrical circuit is insulated through a conduit 125 as shown and leads by the wires 126 to the magnet through a suitable electrical connection 127. A head 130 is bolted to the lower end of the casing 110 100 as shown and carries a register or counter 95 which is so arranged as to be operated by a detent 131 engaging with the armature 91 so that the movement of the armature and consequently the movement of the valve will 115 be recorded. Extending through the side of the head 130 is a shaft 132, at one end of which is a thumb wheel 133 and to the shaft is secured a finger 134 which is utilized as a means to close the valve 92 on its seat and to 120 re-set the armature by manual operation. A glass plate 135 is secured to the end of the head 130 to protect the registering or recording apparatus and through which the registering wheels may be observed. 125

From the above description, it will be seen that the operation of the valve 92 is controlled by an electro-magnetic circuit and a manually operated lever which is used particularly as a part of the controlling means 130

of the automatic train stop mechanism hereinabove described. The valve structure is so related to the other elements of the train stop, that an interruption or discontinuance 5 of the electro-magnetic current will permit the armature to drop and thus allow the pneumatic valve to open, thereby permitting the air pressure to be vented to the atmosphere through ports 118, 120 and whistle 94. 10 The valve 92 is so constructed that all its moving parts are aided by gravity in opening and the valve is so situated that it can be easily and quickly removed for repair and adjustment without necessitating the 15 disconnection of the pipes or wires. Suitable electric contact plugs are so constructed in the connecting flange as to enable the removal of the controlling wires.

The electro-magnet is so constructed as to 20 have a minimum attracting force and a maximum holding force and the armature working with the electro-magnet is so constructed as to reduce the residual magnetism to a minimum.

25 The operation of the installation will now be described.

All parts of the valve mechanism are assumed to be in their normal position as shown. Fluid pressure from the main reservoir H is delivered to the main connection D by suitable connecting pipes and fittings through the restricted passage 31 of fixed capacity to the chamber 16 thence through passage 47 into the chamber 46 and the pressure 30 is then built up in the chambers 16 and 46 which results in the forcing of the piston 14 up and also deflecting the double diaphragm 80 upward. As a result of the piston being forced upward into the chamber 15 the valves 8 and 24 are raised off of 40 their seats against their respective springs 13 and 28.

The upward deflection of the diaphragm 80 causes the shank 64 of the stud 62 to be 45 forced against the stud 60 and the yoke 57 thus causing the double diaphragm 70 to also deflect upward, which results in causing the valve 54 to close upon its seat 53 thus shutting off the communication between the 50 chamber 40 through chamber 41 and port 41' to atmosphere. The brake pipe pressure which is flowing through the supply pipe 35 leading from the engineer's automatic brake valve A to the chamber 36 passes by the 55 valve 8, which is now off its seat 7 into the chamber 6 and as this pressure is less than the pressure on the lower side of the piston 14, or in the chamber 16, no movement of the piston 14 takes place. The fluid pressure 60 then passes by the valve stem 25 and the valve 24, which is now open, through the passage 22 into the chamber 23 through the pipe 48 into the initial pressure reservoir G, thus building up a pressure therein for future use. As the exposed area of the dia-

phragms bounding chamber 23 is less than the area of the other diaphragms and as the pressure in the chamber 46 exceeds that in the chamber 23, no movement of the diaphragms takes place at this time and the 70 diaphragm consequently remains in the uppermost position. Air pressure is thus built up in the chambers 5 and 6 and in the brake-pipe 33, and also through the passage 44 in the chambers 40 and 45 so that an effective 75 operation of pressure will be maintained in the brake-pipe.

The pressure within the chamber 16 is greater than the pressure within the chamber 15, (which last mentioned pressure is obviously equal to the pressure within the brake pipe 33) because of the fact that the pressure within the main reservoir H from which air is supplied to said chamber 16 is, in ordinary air brake systems, greater than the pressure in the brake pipe; the excess pressure being maintained in order to secure a more certain and prompt release of the brakes after they have been applied, and in order to more quickly replenish the supply 90 of air in the auxiliary reservoirs. This is a common feature in air brake systems, and is ordinarily provided for by adjusting the air pump regulator so as to permit the pump to supply air to the main reservoir until the 95 pressure therein shall exceed by a predetermined amount the pressure to be maintained in the brake pipe and auxiliary reservoirs, and by providing a valve held to its seat by a spring of the required stiffness past which 100 air is supplied to the brake pipe through suitable ports provided in the engineer's valve when the same is in the "running" position. The piston 14 is thus held in its uppermost position notwithstanding the fact 105 that the areas of both ends thereof are the same, in the form of my invention illustrated; although it will be appreciated that both ends of the piston need not be of the same area, as the piston may be so designed 110 and proportioned that it will be held in its uppermost position, and the valve 8 held open, by any predetermined excess of pressure to be maintained in the main reservoir of the system.

115 The electro-pneumatic vent valve B is connected to the chamber 16 by passage-way 116 and pipes 32' and 32 and this valve is assumed to be in its normal position when the electro-magnet 190 is energized and the 120 armature is in contact with the magnet which results in the air valve 92 being closed upon its seat 93.

The operation of the train stop is brought about by the opening of the valve 92 which vents the fluid pressure in chamber 16 or by any leak which will vent this chamber. The mechanism for automatically venting the fluid pressure in this instance is an electro-pneumatic valve B which is constructed to 130

be affected by suitable electrical devices located at predetermined distances or blocks along the railroad track. The valve 92 is opened upon deenergizing the electro-magnet 190 which is caused by the interruption or discontinuance of the electric current brought about by the electrical apparatus just referred to, but not shown.

The deenergizing of this magnet allows the armature 91 to drop carrying the valve 92 away from its seat 93 and allowing air pressure in the chambers 16 and 46 to escape to the atmosphere through the whistle 94, for the reason that the passage-way past the valve seat 93 is greater than the area of the restricted passage 31, and the pressure in the chambers 16 and 46 is reduced.

The brake-pipe pressure in the chamber 15 then causes the piston 14 to move into the chamber 16 and thus allows the spring 13 to close the valve 8 upon its seat 7 thereby shutting off the supply from the engineer's automatic brake-valve A to the brake-pipe 33. The valve 24 is also closed upon its seat by the spring 28 thus shutting off the supply of pressure from the chamber 15 to the chamber 23 and the reservoir G, and the closing of the valve 24 also prevents the escape of the stored pressure from the chamber 23 and the reservoir G.

The reduction of pressure in chamber 46 allows the diaphragms 88 and 87 to deflect into the chamber 46 due to the greater pressure in the chamber 23 and which results in carrying the shank 64 of the stud 62 away from the stud 60 of the yoke 57. The unit pressure in chambers 40 and 23 now being equal, the greater area of diaphragm 77 over the diaphragm 78 causes them to deflect into the chamber 23 carrying with it the yoke 57 which causes the valve 54 to leave its seat 53. This operation allows pressure from the chamber 40 to escape to the atmosphere by valve stem 56, valve seat 53 and valve 54 into the chamber 41 escaping to the atmosphere through the restricted port 41.

The valve 54 will remain off its seat 53 until the pressure in the chambers 40 and 45 and brake pipe 33 has been reduced to a predetermined amount, or until the effective pressure on the diaphragm 77 is equal to or just a little less than the effective pressure on the diaphragm 78. At this time the stored pressure in the chamber 23 and reservoir G will cause the diaphragms 77 and 78 to deflect into the chamber 42 carrying with it yoke 57 and the valve 54 thereby closing the valve into its seat 53 and consequently preventing further escape of the pressure to the atmosphere.

The train stop has now made a service application of brakes and is in stop position.

From the foregoing, it will be seen that when the pressure is reduced in chamber 16, the piston 14 will have moved as before men-

tioned, thereby permitting the valve 8 to seat itself, which action will prevent the air pressure from the engineer's valve A from being supplied to the brake pipe 33, and so while the valve 8 is in its closed position, the engineer will be unable to release the brakes. The fact that the valve 8 is seated, will not, however, prevent it from being removed from its seat when the engineer manipulates the automatic brake valve A, so that it will open a port in said valve to the atmosphere, thereby reducing the pressure in chamber 5 which will permit the valve 8 to be unseated by the excess pressure in the brake pipe 33 which will result in a further and heavier application of the brakes.

The train stop will remain in this position until the train has been brought to a standstill. In order to release the brakes and release the train stop, the electro-pneumatic vent valve B must close, but this valve is so located on the engine that it is necessary for the engineer to dismount from his cab in order to gain access to the said valve.

As has been above referred to, the electro-pneumatic valve B is operated to close it by turning the hand or thumb-wheel 133 which is mounted upon the valve casing, a part of the revolution. This wheel is fastened to a spindle mounted adjacent the armature in the head 130 in the center of which spindle is fastened a short lever which will co-act with the armature 91 when the wheel 133 is turned a part of a revolution. The armature will then be forced against the face of the magnet thus closing the valve 92 on its seat 93 thereby shutting off the flow of air pressure to the atmosphere. The closing of this valve allows the main reservoir pressure to build up in chambers 16 and 46 forcing the piston 14 upwardly and deflecting the double diaphragm 80 upwardly as before described.

While the above described construction forms a positive and efficient installation, it is to be noted that the details of construction may be changed without departing from the spirit and scope of my invention.

I desire it also to be understood that the language used in the following claims is intended to cover all of the generic and specific features of the invention herein described, and all statements of the scope of the invention, which as a matter of language might be said to fall therebetween.

Having now described my invention, what I claim and desire to secure by Letters Patent, is—

1. In an automatic train stop device for use with an air brake system having an engineer's brake controlling valve, and a brake pipe leading therefrom and through which air may flow to and from suitable air operated brake mechanism; means adapted to interrupt the flow of air through said brake

6

pipe toward said brake mechanism; means for operating said interrupting means to arrest the flow of air toward said brake mechanism; means for permitting a flow of 5 air from said brake pipe to thereby reduce the pressure therein; means for bringing about the operation of said operating and flow permitting means when the train stop is to be caused to operate; and means for 10 permitting a flow of air through said brake pipe toward said engineer's valve after the train stop has been caused to operate.

2. In an automatic train stop device for use with an air brake system having an engineer's brake controlling valve, and a brake pipe leading therefrom and through which air may flow to and from suitable air operated brake mechanism; a normally open valve adapted to interrupt the flow of air 15 through said brake pipe toward said brake mechanism, and which valve is so constructed and arranged that it will permit a flow of air through said brake pipe toward said engineer's valve after the train stop has been 20 caused to operate; mechanism for operating said valve to close it and arrest the flow of air toward said brake mechanism; means for causing said valve operating mechanism to operate to thereby bring about the operation 25 of the train stop; a conduit leading from said brake pipe and through which air may flow therefrom; a normally closed valve for controlling the flow through said conduit; and means dependent for its operation upon 30 said valve operating mechanism for opening 35 said last mentioned valve.

3. In an automatic train stop device for use with an air brake system having an engineer's brake controlling valve, and a brake pipe leading therefrom and through which air may flow to and from suitable air operated brake mechanism; a valve seat past which air flowing in said brake pipe flows; a puppet valve adapted to seat upon said 40 valve seat, and to open toward said engineer's valve, to thereby permit a flow of air from said brake pipe toward said engineer's valve; means operated by air under pressure for normally holding said valve off 45 its seat; means for causing said valve to seat upon said valve seat to thereby bring about the operation of the train stop; a conduit leading from said brake pipe and through which air may flow therefrom; a normally 50 closed valve for controlling the flow through said conduit; and means for opening said last mentioned valve simultaneously with the movement of said first mentioned valve on to its seat.

60 4. In an automatic train stop device for use with an air brake system having an engineer's brake controlling valve, and a brake pipe leading therefrom and through which air may flow to and from suitable air operated 65 brake mechanism; a valve seat past

which air flowing in said brake pipe flows; a puppet valve adapted to seat upon said valve seat, and to open toward said engineer's valve, to thereby permit a flow of air from said brake pipe toward said engineer's 70 valve; a cylinder; a piston movable within said cylinder and in operative engagement with said valve to normally hold it off its seat; means for supplying air under pressure to said cylinder to thereby operate said piston and hold said valve off its seat; means for releasing the pressure within said cylinder to thereby bring about the closing of said valve on to its seat; a conduit leading from said brake pipe and through which air 75 may flow therefrom; a normally closed valve for controlling the flow through said conduit; means for opening said last mentioned valve simultaneously with the movement of said first mentioned valve on to its seat; and means for closing said last mentioned valve after a predetermined interval.

5. In an automatic train stop device for use with an air brake system having an engineer's brake controlling valve, and a brake pipe leading therefrom and through which air may flow to and from suitable air operated 80 brake mechanism; a valve seat past which air flowing in said brake pipe flows; a puppet valve adapted to seat upon said valve seat, and to open toward said engineer's valve, to thereby permit a flow of air from said brake pipe toward said engineer's valve; a cylinder; a piston movable within 85 said cylinder and in operative engagement with said valve to normally hold it off its seat; means for supplying air under pressure to said cylinder to thereby operate said piston and hold said valve off its seat; means for releasing the pressure within said cylinder to thereby bring about the closing of said valve on to its seat; a conduit leading from said brake pipe and through which air 90 may flow therefrom; a normally closed valve for controlling the flow through said conduit; means for opening said last mentioned valve simultaneously with the movement of said first mentioned valve on to its seat; and means for closing said last mentioned valve after a predetermined interval.

6. In an automatic train stop and in combination with a source of air under pressure, an engineer's brake controlling valve, and a brake pipe leading therefrom and through which air may flow from said source to suitable air operated brake mechanism and from 105 said mechanism through said engineer's valve to the atmosphere; a normally open valve for arresting the flow from said engineer's valve through said brake pipe toward said brake mechanism, and for per- 110 115 120 125 130

- mitting a free flow through said pipe in a reverse direction; air operated means for holding said valve in its normally open position; a conduit communicating with said source of air under pressure and through which air is supplied to said air operated means; a valve for releasing the pressure in said air operated means to thereby permit said first mentioned valve to close when the train stop is to be caused to operate; and means operated by air under pressure for establishing a flow of air from said brake pipe to the external atmosphere when said first mentioned valve moves into its closed position, to thereby reduce the pressure in said brake pipe.
7. In an automatic train stop and in combination with a main reservoir containing air under pressure, an engineer's brake controlling valve and a brake pipe leading therefrom and through which air may flow from said main reservoir to suitable air operated brake mechanism and from said mechanism through said engineer's valve to the atmosphere; a normally open valve for arresting the flow from said engineer's valve through said brake pipe toward said brake mechanism, and for permitting a free flow in a reverse direction; a piston operatively associated with said valve and adapted to hold the same in its normally open position; a cylinder in which said piston operates; a conduit communicating with said main reservoir and through which air is supplied to said cylinder; a valve for releasing the pressure in said cylinder to thereby permit said first mentioned valve to close when the train stop is to be caused to operate; a conduit through which air may flow from said brake pipe to the external atmosphere as said first mentioned valve closes; a normally closed valve for controlling the flow through said conduit; and means for operating said last mentioned valve simultaneously with the closing movement of said first mentioned valve.
8. In an automatic train stop and in combination with a main reservoir, an engineer's brake controlling valve, and a brake pipe leading therefrom and through which air may flow from said main reservoir to suitable air operated brake mechanism, and from said mechanism through said engineer's valve to the atmosphere; a normally open valve for arresting the flow from said engineer's valve through said brake pipe toward said brake mechanism, and for permitting a free flow in a reverse direction; a piston operatively associated with said valve and adapted to hold the same in its normally open position; a cylinder in which said piston operates; a conduit through which air is supplied from said main reservoir to said cylinder to thereby operate said piston and hold said valve in its open position; a valve for releasing the pressure in
- said cylinder to thereby permit said first mentioned valve to close when the train stop is to be caused to operate; a conduit leading from said brake pipe to the external atmosphere; a normally closed valve for controlling the flow of air through said conduit; an initial pressure reservoir; a conduit leading from said brake pipe to said initial pressure reservoir and through which air is supplied thereto; a valve for controlling the flow through said last mentioned conduit, and which valve is held in a normally open position by said piston; and means dependent for its operation upon air under pressure derived from said initial pressure reservoir, and upon the pressure of air within said brake pipe, for operating said last mentioned valve.
9. In an automatic train stop and in combination with a main reservoir, an engineer's brake controlling valve, and a brake pipe leading therefrom and through which air may flow from said main reservoir to suitable air operated brake mechanism, and from said mechanism through said engineer's valve to the atmosphere; a normally open valve for arresting the flow from said engineer's valve through said brake pipe toward said brake mechanism, and for permitting a free flow in a reverse direction; a piston operatively associated with said valve and adapted to hold the same in its normally open position; a cylinder in which said piston operates; a conduit through which air is supplied from said main reservoir to said cylinder to thereby operate said piston and hold said valve in its open position; a valve for releasing the pressure in said cylinder to thereby permit said first mentioned valve to close when the train stop is to be caused to operate; a conduit leading from said brake pipe to the external atmosphere; a normally closed valve for controlling the flow of air through said conduit; a diaphragm operatively connected with said valve and the upper surface of which is subjected to the pressure of the air within said brake pipe; a second diaphragm arranged adjacent and operatively associated with said first mentioned diaphragm, and the lower surface of which is subjected to the pressure of the air within said cylinder; a conduit leading from said brake pipe into the space between said diaphragms; a normally open valve for controlling the flow through said last mentioned conduit; and means whereby said last mentioned valve is closed simultaneously with the closing of said first mentioned valve.
10. In an automatic train stop and in combination with a main reservoir, an engineer's brake controlling valve, and a brake pipe leading therefrom and through which air may flow from said main reservoir to suit-

- able air operated brake mechanism, and from said mechanism through said engineer's valve to the atmosphere; a normally open valve for arresting the flow from said engineer's valve through said brake pipe toward said brake mechanism, and for permitting a free flow in a reverse direction; a piston operatively associated with said valve and adapted to hold the same in its 5 normally open position; a cylinder in which said piston operates; a conduit through which air is supplied from said main reservoir to said cylinder to thereby operate said piston and hold said valve in its open position; 10 a valve for releasing the pressure in said cylinder to thereby permit said first mentioned valve to close when the train stop is to be caused to operate; a conduit leading from said brake pipe to the external atmosphere; a normally closed valve for controlling the flow of air through said conduit; a diaphragm operatively connected with said valve and the upper surface of which is subjected to the pressure of the air 15 within said brake pipe; a second diaphragm arranged adjacent and operatively associated with said first mentioned diaphragm, and the lower surface of which is subjected to the pressure of the air within said cylinder; a conduit leading from said brake pipe into the space between said diaphragms; a normally open valve for controlling the flow through said last mentioned conduit, and which valve is held in a normally open position by said piston; an initial pressure reservoir communicating with the space between said diaphragms; and means for supplying air under pressure to said initial pressure reservoir.
- 20 11. In an automatic train stop device for use with an air brake system having a brake pipe through which air may flow to and from suitable air operated brake mechanism; a conduit leading from said brake pipe to the external atmosphere and through which air may flow to relieve the pressure in said brake pipe; a normally closed valve for controlling the flow of air through said conduit; a diaphragm operatively connected with said 25 valve; means whereby one surface of said diaphragm is subjected to the varying pressure of the air in said brake pipe, and means for subjecting the other surface of said diaphragm to a substantially constant air pressure to thereby accomplish the closing of said valve.
- 30 12. In an automatic train stop device for use with an air brake system having a brake pipe through which air may flow to and from suitable air operated brake mechanism; a conduit leading from said brake pipe to the external atmosphere and through which air may flow to relieve the pressure in said brake pipe; a normally closed valve for controlling the flow of air through said conduit; a diaphragm operatively connected with said valve; means whereby the upper surface of said diaphragm is subjected to the pressure of the air in said brake pipe; a second diaphragm operatively connected with said valve, means whereby one surface of said diaphragm is subjected to the varying pressure of the air in said brake pipe, and means for subjecting the other surface of said diaphragm to a substantially constant air pressure to thereby accomplish the closing of said valve.
- 35 13. In an automatic train stop device for use with an air brake system having a brake pipe through which air may flow to and from suitable air operated brake mechanism, a conduit leading from said brake pipe to the external atmosphere and through which air may flow to relieve the pressure in said brake pipe, a normally closed valve for controlling the flow of air through said conduit, a diaphragm operatively connected with said valve, means whereby one surface of said diaphragm is subjected to the varying pressure of the air in said brake pipe, means for subjecting the other surface of said diaphragm to a substantially constant air pressure to thereby accomplish the closing of said valve.
- 40 14. In an automatic train stop device for use with an air brake system having a brake pipe through which air may flow to and from suitable air operated brake mechanism, a conduit leading from said brake pipe to the external atmosphere and through which air may flow to relieve the pressure in said brake pipe, a normally closed valve for controlling the flow of air through said conduit, a diaphragm operatively connected with said valve, means whereby one surface of said diaphragm is subjected to the varying pressure of the air in said brake pipe, means for subjecting the other surface of said diaphragm to a substantially constant air pressure to thereby accomplish the closing of said valve, and a pressure operated member associated with said valve and acting thereon in a direction to force the said valve against its seat.
- 45 15. In an automatic train stop device for use with an air brake system having a brake pipe through which air may flow to and from suitable air operated brake mechanism; a conduit leading from said brake pipe to the external atmosphere and through which air may flow to relieve the pressure in said brake pipe, a normally closed valve for controlling the flow of air through said conduit, a diaphragm operatively connected with said valve, means whereby one surface of said diaphragm is subjected to the varying pressure of the air in said brake pipe, means for subjecting the other surface of said diaphragm to a substantially constant air pressure to thereby accomplish the closing of said valve, and a pressure operated member acting upon said valve to force it against its seat, and means for subjecting said pressure operated member to a varying air pressure.
- 50 16. In an automatic train stop device for use with an air brake system having a brake pipe through which air may flow to and from suitable air operated brake mechanism; a conduit leading from said brake pipe to the external atmosphere and through which air may flow to relieve the pressure in said brake pipe; a normally closed valve for controlling the flow of air through said conduit; a diaphragm operatively connected with said valve; means whereby the upper surface of said diaphragm is subjected to the pressure of the air in said brake pipe; a second diaphragm operatively connected with said valve, means whereby one surface of said diaphragm is subjected to the varying pressure of the air in said brake pipe, and means for subjecting the other surface of said diaphragm to a substantially constant air pressure to thereby accomplish the closing of said valve.
- 55 17. In an automatic train stop device for use with an air brake system having a brake pipe through which air may flow to and from suitable air operated brake mechanism; a conduit leading from said brake pipe to the external atmosphere and through which air may flow to relieve the pressure in said brake pipe; a normally closed valve for controlling the flow of air through said conduit; a diaphragm operatively connected with said valve; means whereby the upper surface of said diaphragm is subjected to the pressure of the air in said brake pipe; a second diaphragm operatively connected with said valve, means whereby one surface of said diaphragm is subjected to the varying pressure of the air in said brake pipe, and means for subjecting the other surface of said diaphragm to a substantially constant air pressure to thereby accomplish the closing of said valve.

phragm spaced apart from and adapted to operatively engage said first mentioned diaphragm; means for subjecting the under surface of said second mentioned diaphragm 5 to air under pressure; and means for supplying air under pressure to the space between said diaphragms.

16. In an automatic train stop device for use with an air brake system having a brake pipe through which air may flow to and from suitable air operated brake mechanism; a conduit leading from said brake pipe to the external atmosphere and through which air may flow to relieve the pressure in said 10 brake pipe; a normally closed valve for controlling the flow through said conduit; a diaphragm operatively connected with said valve; means whereby the upper surface of said diaphragm is subjected to the pressure 15 of the air in said brake pipe; a second diaphragm associated with said first mentioned diaphragm and spaced apart therefrom; means for subjecting the under side of said second mentioned diaphragm to air under 20 pressure; means for relieving the air pressure acting upon said second mentioned diaphragm; an initial pressure reservoir connected with the space between said diaphragms; a conduit through which air under 25 pressure is supplied from said brake pipe to the space between said diaphragms and to said initial pressure reservoir; a valve for controlling the flow of air under pressure through said last mentioned conduit; and 30 means for operating said last mentioned valve.

17. In an automatic train stop device for use with an air brake system having a brake pipe through which air may flow to and from suitable air operated brake mechanism; a normally open valve adapted to interrupt the flow of air through said brake pipe; a cylinder; a piston movable within 40 said cylinder and operatively associated with said valve for normally holding said valve off its seat; means for supplying air under pressure to the lower end of said cylinder to thereby operate said piston and hold said valve off its seat; means for releasing the 45 pressure within said cylinder to thereby bring about the closing of said valve; a conduit leading from said brake pipe to the external atmosphere; a normally closed valve for controlling the flow of air through said conduit; and means operated by air under pressure derived from said brake pipe for opening 50 said last mentioned valve; and means operated by air under pressure derived from the upper end of said cylinder for closing said last mentioned valve.

18. In an automatic train stop device for use with an air brake system having a brake pipe through which air may flow to and from suitable air operated brake mechanism; a normally open valve adapted to interrupt the flow of air through said brake pipe; a cylinder; a piston movable within 55 said cylinder and operatively associated with

said valve for normally holding said valve off its seat; means for supplying air under pressure to the lower end of said cylinder to thereby operate said piston and hold said valve off its seat; means for releasing the 60 pressure within said cylinder to thereby bring about the closing of said valve; a conduit leading from said brake pipe to the external atmosphere; a normally closed valve for controlling the flow of air through said conduit; means operated by the pressure of the air in said brake pipe for opening said last mentioned valve; means operated by air under pressure for closing said last mentioned valve; means independent of said 65 valve operating means and operated by air under pressure for forcing said last mentioned valve against its seat; and means for relieving said valve operating means from the action of said pressure operated forcing 70 means when the train stop device is to be caused to operate.

19. In an automatic train stop device for use with an air brake system having a brake pipe through which air may flow to and from suitable air operated brake mechanism; a normally open valve adapted to interrupt the flow of air through said brake pipe, a cylinder, a piston movable within said cylinder and operatively connected with said valve for normally holding said valve off its seat; means for supplying air under pressure to the lower end of said cylinder to thereby operate said piston and hold said valve off its seat, means for releasing the 75 pressure within said cylinder to thereby bring about the closing of said valve; a passage through which air under pressure from said brake pipe is supplied to the upper end of said cylinder, a conduit leading from said brake pipe to the external atmosphere; a normally closed valve for controlling the flow of air through said conduit; means operated by air under pressure derived from said brake pipe for opening 80 said last mentioned valve; and means operated by air under pressure derived from the upper end of said cylinder for closing said last mentioned valve.

20. In an automatic train stop device for use with an air brake system having a brake pipe through which air may flow to and from suitable air operated brake mechanism; a normally open valve adapted to interrupt the flow of air through said brake pipe; a cylinder; a piston movable within said cylinder and operatively connected with said valve for normally holding said valve off its seat, means for supplying air under pressure to the lower end of said cylinder to thereby operate said piston and hold said valve off its seat, means for releasing the 90 pressure within said cylinder to thereby bring about the closing of said valve, a passage through which air under pressure 95 derived from said brake pipe for opening 100 said last mentioned valve; and means operated by air under pressure derived from the upper end of said cylinder for closing said last mentioned valve.

- from said brake pipe is supplied to the upper end of said cylinder, a conduit leading from said brake pipe to the external atmosphere; a normally closed valve for controlling the flow of air through said conduit; means operated by air under pressure derived from said brake pipe for opening said valve, a conduit leading from the upper end of said cylinder and discharging into a chamber located adjacent said valve operating means, and through which conduit air may flow from the upper end of said cylinder to thereby subject said valve operating means to pressure and accomplish the closing of said last mentioned valve; a normally open valve for controlling the flow through said last mentioned conduit, and means whereby said last mentioned valve is held in an open position by said piston.
21. In an automatic train stop device for use with an air brake system having a brake pipe through which air may flow to and from suitable air operated brake mechanism; a normally open valve adapted to interrupt the flow of air through said brake pipe; means operated by air under pressure for holding said valve in its open condition, means for relieving said holding means from the action of said air under pressure to thereby bring about the closing of said valve, a conduit leading from said brake pipe to the external atmosphere, a normally closed valve for controlling the flow of air through said conduit, means operated by the pressure of air in said brake pipe for opening said last mentioned valve; means operated by air under pressure derived from said brake pipe for closing said last mentioned valve; and means operated by air under pressure and controlled by the relieving means aforesaid for forcing said last mentioned valve against its seat.
22. In an automatic train stop device for use with an air brake system having a main air reservoir, an engineer's brake controlling valve, and a brake pipe through which air may flow to and from suitable air operated brake mechanism, a normally open valve adapted to interrupt the flow of air through said brake pipe, a cylinder, a piston movable within said cylinder and adapted to hold said valve in its normally open position, a conduit communicating with said main reservoir and with said cylinder a through which air under pressure is supplied to said cylinder to thereby hold said valve off its seat, means for relieving the air pressure in said cylinder to thereby permit said valve to close, a conduit leading from said brake pipe to the external atmosphere, a normally closed valve for controlling the flow of air through said conduit, means operated by the pressure of air in said brake pipe for opening said last mentioned valve, means operated by air under pressure derived from said brake pipe for closing said last mentioned valve, means operated by air under pressure for forcing said last mentioned valve against its seat, and a passage leading from said cylinder and through which air under pressure is supplied to the means for forcing said last mentioned valve against its seat.
23. In an automatic train stop, a non-release valve, a piston operated by differential pressure, a pair of double diaphragms, an initial pressure reservoir, means operated by the aforesaid piston for controlling the supply of fluid pressure to said initial pressure reservoir.
24. In an automatic train stop, a non-release valve, a piston operated by differential pressure, a pair of double diaphragms, an initial pressure reservoir, means operated by the aforesaid piston for controlling the supply of fluid pressure to said initial pressure reservoir, electro-pneumatic means for controlling the operation of said piston.
25. In an automatic train stop, a valve structure comprising a plurality of sections, a non-release valve in one of said sections, guiding and securing means for said valve, a cylinder and a piston for operating said valve, a valve for venting the brake pipe pressure and a pair of double diaphragms for operating said last mentioned valve.
26. In a device of the class described, a double diaphragm consisting of a pair of diaphragms secured together at their peripheries a space ring between the diaphragms at their peripheries, and a plurality of concentric space rings loosely mounted between the respective diaphragms.
- In witness whereof I have hereunto set my hand at Oroville, county of Butte and State of California, this 1st day of Sept., 1916.
